UNITED STATES PATENT OFFICE

CHARLES A. WOOD, OF CLAY CENTER, KANSAS

TOY AXLE STAMPING AND CUTTING MACHINE

Application filed April 10, 1929. Serial No. 354,085.

My invention relates to a shearing and stamping machine for use in the manufacture of axles for wheeled toys.

The object of my invention is to provide 5 a combined stamp and shear to be used in the fabrication of axles for wheeled toys.

Another object of my invention is to provide a mechanism that will in one operation trim and flatten a wire nail or similar piece 10 of metal for use as an axle in wheeled toys.

A still further object of my invention is to provide a mechanism of the kind described actuated by a lever and having cams for the propulsion and retraction of the stamping 15 and cutting elements.

A still further object of my invention is to provide a mechanism of the kind described in which the stamping and shearing elements are actuated by the cam action of a lever and 20 the cam action is timed to propel the stamping and shearing elements to flatten and trim the axle in one operation.

These and other objects will hereinafter be more fully explained.

25 Referring to the drawings:

Fig. 1 is an elevation of the working parts of the machine with one of the side plates removed and the cap screws and pin in cross section and the jaws in the open position.

30 Fig. 2 is a fragmentary longitudinal section of the machine with the working parts in the position shown in Fig. 1.

Fig. 3 is a fragmentary elevation of the machine taken in an opposite view from that 35 shown in Fig. 1, illustrating the closed position of the jaws with parts removed for the purpose of illustration.

Fig. 4 illustrates a toy automobile with its axle held in position preparatory to the 40 stamping and trimming operation with regard to the jaws of the machine.

Fig. 5 illustrates the completion of the operation of stamping and trimming the axle.

45 Fig. 6 is a fragmentary view of a portion of a toy automobile and one wheel illustrating the formation of the end of the axle after the stamping and cutting operation.

A lever 1 is rigidly connected to a member 2 by the bolts 3 and 4 which also position

the retracting arms 5 and 6. A cam member 7 is fitted on the lower extremity of the lever 1 and adjacent to the member 2 as shown. The lower extremity of the member 2 is formed as a cam in the manner illustrated. 55 Let A designate the surface of the cam portion on the member 2 and B designate the surface of the cam portion on the member 7, the member 7 and the member 2 participate in movement and are trunnioned by the pin 8 carried in the side plates 9 and 10.

The side plates 9 and 10 are rigidly connected by means of rivets or cap screws and spaced by the frame portions 11, 12, and 13, the frame portion 13 being rigidly fastened 60 to the base member 14 by the cap screws 15 and 16. The frame portions 11 and 12 act as guides for the movable jaws 17 and 18 which are slidably positioned between the sides 9 and 10 and the said guides. The pins 17' and 18' threadedly engage the movable jaws 17 and 18 respectively in a rigid manner and extend through the slots 19 and 20 in the side plates 9 and 10 respectively and engage in the arcuated cuts 21 and 22 in the 65 retracting arms 6 and 5 respectively.

The stationary jaw 23 is positioned upon the shims 24 and 25, which rest upon the member 13, and against the spacer 27. The cap screw 26 and the plate 26' position the shims and jaw 23 as shown. The cap screw 28 extending through the slot 29 in the side plate 9 and the slot 30 in the spacer 27 threadedly engages the stationary jaw 23 and holds the jaw rigidly in place. 80

The upper extremity of the jaw 17 slidably engages the cam surface A and the upper extremity of the jaw 18 slidably engages the cam surface B. When the lever arm is rocked in the direction shown by the arrow 85 in Fig. 1, by means of the handle 31, the cam surfaces A and B propel the jaws 17 and 18 respectively to the positions illustrated in Fig. 3.

The lower extremity of the jaw 17 is placed 90 approximately against the upper surface of the stationary jaw 23 by reason of the cam surface A engaging with the upper extremity of the jaw and the jaw 18 passes the edge C of the stationary jaw 23 in the man-

ner shown at D by reason of the engagement of its upper extremity with the cam surface B. The slots 21 and 22 in the retracting arms 6 and 5 respectively function only to retract the jaws 17 and 18 into the position shown in Figs. 1 and 2 after the completion of the operation shown in Fig. 3. The slots are designed to allow free downward movement of the jaws and are not expected to transmit any force in the stamping and trimming operation.

An example of the work performed by this machine is illustrated in Figs. 4, 5, and 6. Fig. 4 illustrates the jaws in the open position. A toy automobile 32 having wheels 33 and a wire nail or similar rod member 34, to trunnion the wheels, is placed in the position shown in Fig. 4 with respect to the jaws. The end of the nail at E is positioned between the jaws at the beginning of the operation. Fig. 5 illustrates the completion of the operation, the jaw 17 has pressed the nail against the jaw 23 and the jaw 18 has severed the portion E, leaving the end of the nail or axle in the shape illustrated at F in Fig. 6. In this manner the nail 34 now holds the wheels 33 rotatable on the toy 32 and the wheel 33 adjacent the portion F of the axle cannot pass over this flattened end. By the use of this mechanism the end of the axle is flattened and trimmed in one operation. I have found that this saves considerable time and expense in the manufacture and assembly of wheeled toys.

Such modifications may be used as come within the scope of the appended claim and what I do claim as new and desire to secure by Letters Patent is:

In a mechanism for forming axles for wheeled toys, to trim and flatten the end of the axle, a stamping element comprising two jaws, one stationary and one movable and the movable jaw being separately slidable from the stationary jaw and being propelled toward the stationary jaw by a cam surface on a lever and being retracted from the stationary jaw by reason of a laterally extending pin engaging in an arcuated slot in an arm connected to the lever, and a shearing member propelled past the edge of the stationary jaw in the manner of a cutter and the propulsion of the shearing member being actuated by another cam surface on the lever and being retracted by reason of a laterally extending pin engaging in an arcuated slot in an arm affixed to the lever and the actuating cam mechanism timed to propel the flattening and shearing members in the same movement of the lever.

In testimony whereof I affix my signature.
CHARLES A. WOOD.
